United States Patent Office

Des. 223,325
Patented Apr. 4, 1972

223,325

BEVERAGE DISPENSER

Dana W. Mox, Glenview, Ill., assignor to Karma Division of Brandt Automatic Cashier Company, Addison, Ill.

Filed Oct. 29, 1970, Ser. No. 25,707

Term of patent 14 years

Int. Cl. D15—08

U.S. Cl. D94—3

FIG. 1 is a perspective view of a beverage dispenser showing my new design;

FIG. 2 is a front elevational view thereof;

FIG. 3 is a side elevational view, the opposite side being a mirror image of the side shown;

FIG. 4 is a rear elevational view; and

FIG. 5 is a top plan view.

I claim:

The ornamental design for a beverage dispenser, as shown and described.
